UNITED STATES PATENT OFFICE.

EDWARD J. RAMSEY, OF NEW YORK, N. Y.

STITCH-DOWN WELTLESS SHOE.

Application filed February 18, 1927. Serial No. 169,155.

This invention relates to improvements in the manufacture of shoes, technically known as stitch-down welt shoes, and the principal object is to provide a construction in which the welt is eliminated and at the same time a tearing apart or ripping of the outer sole from the inner sole is prevented.

Another object is to provide a welt-less shoe wherein reinforcement of the connection between the outer sole and the upper is provided for by means of a separate connection running through the outer sole, an inner sole and the upper, independently of a somewhat similar connection which runs through these parts last-mentioned.

Various other objects and advantages of the invention than those hereinabove mentioned will be specifically pointed out or will be apparent hereinafter in the course of the below detailed description of the form of the invention shown, in the accompanying drawing, as a preferred one of the various possible embodiments of the invention; it being understood, naturally that such form is merely illustrative of one of the many possible combinations and arrangements of parts well calculated to attain the objects of the invention, and hence said detailed description of such form is not to be taken as at all defining or limiting the invention itself. That is to say, the scope of protection contemplated is of course to be taken from the appended claims, interpreted as broadly as is consistent with the prior art.

In said drawing:

Fig. 1 is a transverse section showing a form now preferred as above;

Fig. 2 is a similar view showing a variation of said form;

Fig. 3 is a similar view showing another variation; and

Fig. 4 is a similar view showing still another variation.

Referring to the numerals on the drawing, in each view there is indicated at 5 the upper of a shoe, said upper having its marginal portions turned out in the usual way as indicated at 6. At 7 is indicated an insole and 8 an outsole.

Also, in each view, the upper 5 and the insole 7 are connected together by means of a stitch 9 which passes through these parts, angling from the junction between the main part of the upper 5 and the portions 6 thereof, downwardly and inwardly. In addition

there are a pair of stitches 10 and 11 which connect the turned out upper portions 6, the insole 7 and the outsole 8. These stitches clamp down all three elements 6, 7 and 8, over a considerable part of the width of portions 6; and are desirably disposed parallel and vertical, although they may also be angled in directions to increase resistance to any tendency of the parts to separate upon the application of outward pressure by the foot within the shoe.

In Figs. 2 and 3 there is an additional stitch 12, which goes through the insole 7 but not through the outsole 8.

In Fig. 2, there is shown in the shoe a second insole 14, not wide enough to extend beyond the line of stitching 9; and the additional stitch 12 goes through this second insole 14.

In Fig. 3, there is not only a second insole, 14, as in Fig. 2, but a liner 15. The marginal portions of this liner are inturned and extended between the insoles 7 and 14 as shown; and here the additional line of stitching 12 goes through the two insoles and the liner.

In Fig. 4, only the three lines of stitching 9, 10 and 11 are employed as in Fig. 1. Here, however, while the liner 15' is employed, the same is laid flat against the top of the second insole 14. The marginal portions of the liner are out-turned, so that these marginal portions lie between the out-turned marginal portions 6 of the upper and the first insole 7. In this variation, the stitches 9, 10 and 11 all pass through the upper, the liner and the first insole 7, none pass through the second insole 14, while two of the stitches, the stitches 10 and 11, pass also through the outsole 8 as in the case of Fig. 1.

The advantages of the construction described will be obvious, providing as it does a weltless triple-stitch-down construction of shoe in which the likelihood of the tearing apart of the shoe at the junction between the outer sole and the inner sole, and between the upper and the soles, due to the outward pressure of the foot within the shoe against the usual welt location, is minimized and substantially eliminated.

Inasmuch as many changes could be made in the above construction, and many apparently widely different embodiments of the invention could be made without departing from the scope thereof, it is intended that all matter contained in the above description or

shown in the accompanying drawing shall be interpreted as illustrative and not in a limiting sense.

It is also to be understood that the language contained in the following claims is intended to cover all the generic and specific features of the invention herein described and all statements of the scope of the invention which, as a matter of language, might be said to fall therebetween.

I claim:

1. A stitch-down weltless shoe having structural elements including an outsole, an insole and an upper out-turned to have marginal portions overlying edge portions of the two soles, said shoe also including a structural element located between the upper and the insole, and a plurality of lines of stitches each going through a plurality of said elements, two of said stitches going through said marginal portions and the two soles.

2. A stitch-down weltless shoe having structural elements including an outsole, an insole and an upper out-turned to have marginal portions overlying edge portions of the two soles, said shoe also including a structural element located between the upper and the insole, and a plurality of lines of stitches each going through a plurality of said elements, two of said stitches going through said marginal portions and the two soles and also through the last-mentioned element.

3. A stitch-down weltless shoe having structural elements including an outsole, an insole and an upper out-turned to have marginal portions overlying edge portions of the

two soles, said shoe also including a structural element located between the upper and the insole, and a plurality of lines of stitches each going through a plurality of said elements, two of said stitches going through said marginal portions and the two soles and three of said stitches going through the upper and the insole.

4. A stitch-down weltless shoe having structural elements including an outsole, an insole and an upper out-turned to have marginal portions overlying edge portions of the two soles, said shoe also including a structural element located between the upper and the insole, and a plurality of lines of stitches each going through a plurality of said elements, two of said stitches going through said marginal portions and the two soles, one other of said stitches going through the upper and the insole but not through the out-sole.

5. A stitch-down weltless shoe having structural elements including an outsole, an insole and an upper out-turned to have marginal portions overlying edge portions of the two soles, said shoe also including a structural element located between the upper and the insole, and a plurality of lines of stitches each going through a plurality of said elements, two of said stitches going through said marginal portions and the two soles and three of said stitches going through the upper and the insole.

In testimony whereof I affix my signature.

EDWARD J. RAMSEY.
